RELAY CONNECTOR HOUSING

James Pritulsky, Harrisburg, Pa., assignor to
AMP Incorporated, Harrisburg, Pa.

Filed Oct. 2, 1969, Ser. No. 19,394

Term of patent 14 years

Int. Cl. D13—03

U.S. Cl. D26—1

FIG. 1 is a perspective view of a relay connector housing showing my new design;

FIG. 2 is a rear elevational view of the device shown in FIG. 1;

FIG. 3 is a front elevational view of the device shown in FIG. 1;

FIG. 4 is an elevational view of the device looking down from the top of FIG. 2; and

FIG. 5 is an elevational view looking in from the left side of FIG. 2.

I claim:

The ornamental design for relay connector housing, substantially as shown.
